UNITED STATES PATENT OFFICE.

HUGO M. KUNIOLM, OF GARDNER, MASSACHUSETTS, ASSIGNOR TO CHILDREN'S VEHICLE CORPORATION, OF EAST TEMPLETON, MASSACHUSETTS, A CORPORATION OF MASSACHUSETTS.

FOLDING GOCART.

Application filed December 29, 1924. Serial No. 758,529.

This invention relates to a folding baby-carriage or go-cart of the type in which the body is made largely of fabric or other flexible material and is removable from the frame when the car is to be folded.

It is the general object of my invention to improve the construction of the folding frame and of the running gear of such a cart, to the end that the parts may be firmly held in operative position and that they may be quickly and easily foldable when so desired.

Important features of my invention relate to improved devices for locking and releasing the handle of the gocart; to an improved cam mechanism for folding the wheel frame members; and to other arrangements and combinations of parts which will be hereinafter described and more particularly 20 pointed out in the appended claims.

A preferred form of the invention is shown in the drawings in which—

Fig. 1 is a side elevation of my improved go-cart;

Fig. 2 is a partial end view thereof, looking in the direction of the arrow 2 in Fig. 1;

Fig. 3 is a detail side elevation of the handle locking device, looking in the direction of the arrow 3 in Fig. 2;

Fig. 4 is a perspective view of a portion of one of the latches;

Fig. 5 is a partial sectional plan view, taken along the line 5—5 in Fig. 1;

Fig. 6 is an end elevation of the parts shown in Fig. 5; and

Fig. 7 is a view similar to Fig. 6 but showing the parts in a different position.

Referring particularly to Fig. 1, my improved go-cart comprises a main frame 10 to which a head frame 11 and a foot frame 12 are pivoted. Foldable braces 13 and 14 are provided at each side of the carriage to lock the head and foot frames in operative position, as shown in Fig. 1.

A handle 15 is provided with spaced side members 16 which are pivoted at 17—17 to the side members of the head frame 11. A cross brace 18 is preferably provided for the head frame at the point of attachment of the handle.

Each handle member 16 has a depending projection 19 extending below its pivot 17 for engagement by a latch 20. Each latch 20 (Fig. 4) comprises separated arms extending on each side of a spring plate 21 to

which the latch 20 is firmly secured. The spring plate 21 is mounted on the head frame 11, preferably by inserting the end of the spring plate between the head frame 11 and an end of the brace 18. The arms of the latch 20 also embrace the head frame 11 and extend beyond the frame in position for engagement by the depending portion 19 of a side member 16 of the handle.

One of the latch arms is provided with a cam surface 22, so that the latch will be pressed yieldingly backward as the handle is swung to operative position. When once in position, however, the handle is positively held by the latch and cannot be folded until after manual release thereof.

For such manual release, a lever 24 is pivoted at 25 to a downwardly extended portion of one of the spring plates 21, and a link 26 connects the lever to a correspondingly extended portion of the other spring plate 21. As the lever 24 is pulled upward, the spring plates 21 are pulled inward, thus simultaneously withdrawing the latches 20 and releasing the handle 15, which may then be swung downward as indicated in dotted lines in Fig. 1, to its folded position.

A body 30 of any desired construction is supported from the head and foot frames 11 and 12, as by straps 31 and hooks 32, and is also preferably secured by a strap 33 and hook 34 to the main frame 10. The body 30 is thus easily removed whenever it is desired to fold the carriage or for any other purpose.

The wheels W are mounted on the wheel frame members 40 and 41 (Fig. 7) which extend longitudinally of the main frame 10 and which are pivoted at 42 to depending end portions of the main frame.

For folding the wheel frames, I provide the wheel frames with cam bars 43 and 44, which are substantially identical in construction but which are secured to the frame members 40 and 41 in reversed positions, as clearly shown in Fig. 5. An actuator 45 (Figs. 1 and 6) is pivoted at 47 (Fig. 1) to each side of the main frame 10. Upwardly extending portions 48 of said actuator are connected by links 50 to the head frame 11 near its pivotal connection with the main frame 10.

As the head frame 11 is moved in the direction of the arrow b (Fig. 1) to folded position, the actuator 45 moves in the direc-

tion of the arrow *c*. As the actuator 45 is thus moved, the transverse lower portion 51 of said actuator first engages the narrow end of the cam bar 44 and thereafter engages the wide end of the cam bar 43. This successive engagement moves the wheel frames and wheels successively to folded position, as indicated in Fig. 7, the wheel frame member 41 reaching its folded position somewhat in advance of the wheel frame member 40.

When unfolding the carriage, the parts move in the reverse order, and when nearly open the wheel frame members 40 and 41 are engaged by cam portions 52 of the actuator 45, which completes their movement to full operative position.

By forming the cam bars 43 and 44 of identical construction, I reduce the number of different parts required in manufacture and by attaching them in reverse positions to the wheel frame members I obtain the successive action which is essential to this type of running gear.

25 When folding the carriage or go-cart, the release lever 24 is first used to release the handle 15, which is thereafter swung downward, as indicated by the arrow *a* in Fig. 1. The braces 13 are then pulled upward enough to release the head frame member 11, which is then swung in the direction of the arrow *b* in Fig. 1, thus folding the head frame 11 and handle 15 against the upper side of the main frame 10 and at the same time folding the running gear against the lower side of the main frame 10. The foot frame 12 is then released and folded against the head frame 11. The entire frame and running gear 40 is thus foldable to a very compact unit which may be easily carried aboard a car or taken into a house.

It will be understood that the body 30 is removed from the frame before the folding operation is commenced. This body 30 is also preferably collapsible so that

it also may be folded to occupy a relatively small space.

Having thus described my invention and the advantages thereof I do not wish to be limited to the details herein disclosed otherwise than as set forth in the claims, but what I claim is:—

1. In a folding go-cart, a main frame, wheel frame members pivoted at each end to an end of said main frame, means to fold said wheel frame members successively against the under side of said main frame, a head frame foldable against the upper side of said main frame, an actuator for said wheel frames movable with said head frame, a handle on said head frame foldable against the outer side thereof, and a foot frame foldable against said head frame and handle.

2. In a folding go-cart, in combination, a head frame having two spaced side members, a handle having side members pivoted to said head frame side members, a spring latch for locking each head frame side member to the corresponding handle side member, a release handle lever pivoted to an extension of one latch, and a link connecting said lever to an extension on the other latch, whereby said latches may be simultaneously released.

3. In a folding go-cart, in combination, a head frame having two spaced side members, a handle having two side members pivoted to said head frame side members, and a spring latch for locking each head frame side member to the corresponding handle side member, each latch having locking elements embracing a head frame side member and yieldingly engaging the associated handle side member when the latter is moved to operative position, and positively preventing reverse movement thereof until said latches are manually withdrawn.

In testimony whereof I have hereunto affixed my signature.

HUGO M. KUNIHLOM.
